JACOB P. TIRRELL, OF CHARLESTOWN, AND S. G. BRETT, OF SOMERVILLE, MASSACHUSETTS, ASSIGNORS TO THEMSELVES, M. S. MARSHALL, AND HIRAM WHITNEY; AND SAID JACOB P. TIRRELL ASSIGNOR TO HIRAM WHITNEY; AND SAID BRETT ASSIGNOR TO M. S. MARSHALL.

Letters Patent No. 86,712, dated February 9, 1869.

IMPROVEMENT IN PAPER-FILES.

The Schedule referred to in these Letters Patent and making part of the same.

To all whom it may concern:

Be it known that we, JACOB P. TIRRELL, of Charlestown, and S. G. BRETT, of Somerville, both in the county of Middlesex, and State of Massachusetts, have invented certain Improvements in "Bill-Files," and we hereby declare the following to be a full, clear, and exact description thereof, reference being had to the accompanying drawings, in which—

Figure 1 is a perspective view of our file, with clamp holding papers.

Figure 2 is a perspective view of our file, with clamp raised.

The object of our invention is to produce a file for filing papers, that will allow of the removal of one paper without disturbing others, and that will firmly hold papers without perforating them.

Our invention consists of a flat board, of any suitable material, upon which the papers to be filed are placed, and a clasp, or clamp, which is held upon the paper by springs.

In the drawings—

A is a board, of suitable material, upon which papers to be filed are placed.

B is a smaller board, adjusted over the board A.

To the centre of B are attached the braces c and c'. These braces operate as hinges, turning, as they do, in sockets fast to B, in the centre.

Attached to these hinges or braces c and c', at m, are springs d and d'.

These springs coil around the braces c and c' at m, and then extend to A, where the ends are formed into helical springs, and are there made fast in A at h.

The upper surface of B is bevelled to the edge from the centre, so that when B is raised, as shown in fig. 2, this bevelling allows the board B to come above the point of equal pressure by the springs on the sides, thus holding board B up, but a slight pressure upon the upper side of board B overcomes this upward action of the springs d and d', and the board B comes down firmly upon the papers F, where it holds them, by the opposing action of the springs d and d'.

The arms e and e', attached to B, serve to keep the papers in place.

e is a ring, by which to raise board B.

This operation is simple and convenient, for it allows of withdrawing papers without disturbing others.

These files are cheaply made, and are very durable.

Having fully described our invention, What we claim as new, and desire to secure by Letters Patent, is—

The combination of board B, hinges c and c', attached to B, as described, springs d and d', arms e and e', and board A, when these devices are constructed and arranged to form a bill-file, substantially as described.

In testimony whereof, we have signed our names to this specification, in the presence of two subscribing witnesses.

JACOB P. TIRRELL.
S. G. BRETT.
